UNITED STATES PATENT OFFICE.

HOWARD LYON, OF GLOUCESTER CITY, NEW JERSEY, ASSIGNOR TO WELSBACH LIGHT COMPANY, A CORPORATION OF NEW JERSEY.

IGNITION DEVICE.

1,118,942.

Specification of Letters Patent.

Patented Dec. 1, 1914.

Application filed October 7, 1910. Serial No. 585,772.

To all whom it may concern:

Be it known that I, HOWARD LYON, a citizen of the United States, and a resident of Gloucester City, in the county of Camden and State of New Jersey, have invented certain new and useful Improvements in Ignition Devices, of which the following is a description.

My invention relates to electrical ignition devices for gas burners and has for its object the production of an igniting filament of improved form, capable of better withstanding the effects of the high temperatures to which such filaments are subjected. 10 As is well known, such filaments are usually composed of platinum or an alloy of platinum, and in order to secure a high resistance and a concentrated heating effect with a minimum of current, it is usual to make the filament of extremely minute cross section. 15 Such material when warmed by an electric current in the presence of an explosive mixture of gas and air is acted upon catalytically and heated to an extremely 20 high temperature by chemical action. This high temperature tends to melt and destroy the filament.

It is highly desirable that the ignition device shall be capable of operation when subjected to the current from a single dry cell. In order that this may be accomplished it is necessary to concentrate the heating effect as much as possible by reducing the cross section of the igniting filament. 25 Such reduction of course increases its resistance and thereby determines the length of filament that can be used, that is, the filament cannot exceed a certain length in order that its resistance may be kept down to allow the passage of a current of sufficient strength (preferably from a single cell) to cause ignition. These extremely fine filaments are usually soldered at their ends to suitable conductors, such as leading in wires, for applying the current thereto. Such conductors being of comparatively great cross section and large heat capacity necessarily abstract heat from the filament and rapidly cool the ends thereof, 40 so that in case the filament extends in a straight line from one lead to the other, the only portion of the filament which is effective for initiating the catalytic action of the gas is a very short length thereof situated midway between its ends which I term

the effective portion. This effective portion is at all times the hottest part of the filament and the most likely to be consumed or fused during ignition, so that such filaments almost invariably give way at this point. 60 The ignition filament also parts with heat by radiation and by convection of the surrounding gas which take place in all directions. The fact that the filament, the mass of which is almost inappreciable, is necessarily in close proximity to the leading in wires whose mass is comparatively very great and usually also to the metal forming the body of the igniter, all of which is at a low temperature, means relatively great 65 heat losses which are subtracted from the effectiveness of the igniting current. These radiation and convection losses are proportionately less in a filament formed as a spiral or helix than in one formed as a straight 70 line, for the reason that adjacent coils of the helix protect or blanket each other, and it has been proposed heretofore to form the filament as a helix. This form, however, is open to the objection that it either increases 75 the length of the filament, thereby increasing its resistance and necessitating an increase in the battery voltage, or else it means that the distance between the leading in wires or conductors must be decreased 80 which brings them closer to the central or effective portion of the filament which increases the heat losses thereof.

I have discovered that the most effective and efficient form for the filament is that of a partial spiral or helix, that is a filament having straight ends and a loop or helix therebetween. It is an advantage for such helix to have more than one convolution in order to obtain the blanketing effect of one 90 coil upon its neighbor, but the helix should not have too many convolutions as this necessitates bringing the leading in wires too close to the effective portion of the filament. I prefer therefore to form the helix 95 with only two or three convolutions. I have obtained excellent results with a filament of this form. The effective portion of the filament seems to be protected in some way by the gas within the helix; perhaps the sudden 100 expansion thereof when ignition occurs causes it to convectively remove heat units from the effective or hot portion of the filament and further the gas within the helix 105 by its expansion pushes away the hot prod- 110

ucts of combustion immediately after an ignition.

In order that the invention may be more clearly understood, reference is hereby made to the accompanying drawing, in which—

Figure 1 is a side elevation of an inverted gas burner provided with an igniter constructed in accordance with my invention; Fig. 2 is an enlarged detail section of the igniter shown in Fig. 1, and Fig. 3 is a section on line 3—3 of Fig. 2. Fig. 4 is a greatly magnified side view of the filament, and Fig. 5 is a similar view of a modification.

The igniter comprises a tubular body 1, preferably of brass, secured by a set screw 2 upon a nipple 3 riveted to the canopy 4 of the burner. A baffle plate 5 extends across the bore of the tube 1 and oppositely disposed windows 6 are formed in the walls of said tube above the baffle plate. The filament 7 consisting of a wire of platinum or platinum alloy is formed as shown in Fig. 4 with a central spiral or helix 8 consisting of two convolutions and straight ends 9 extending outwardly therefrom. The ends of the filament are soldered to the leading in wires 10 and 11 and the axis of the helix is at right angles to a straight line drawn from one extremity of the filament to the other. The wire 10 is electrically connected to a metallic sleeve 12 held by a set screw 13 and the wire 11 is similarly connected to a metallic bolt 14 carried by the insulator 15 which is set in the sleeve 12. A metal block 16 is threaded on the bolt 14 and has a bore 17 and binding screw 18 for holding the line wire 19 which leads to one side of the battery, the electrical circuit being completed through the fixture and gas pipe 20. The filament is protected against excessive temperature during ignition by reason of the fact that the baffle plate 5 permits only a small percentage of the ascending gas to approach the filament, and at the same time atmospheric air is permitted to enter freely through the inlets or windows 6. The effect of this structure is to produce in the immediate vicinity of the filament an ignitable mixture of minimum richness, so that the heat due to combustion will be a minimum.

In operating the apparatus with one dry cell the temperature produced in the filament will be such as to initiate catalytic action of the gas, which rapidly increases its temperature to that required for ignition. The temperature produced by the electric current of itself is preferably insufficient to cause ignition. The amount of current required to initiate catalytic action in a wire formed into a two or three turn spiral at the center is appreciably less than for the same wire in a straight form because of the heat conserving effect of the adjacent loops of the spiral.

The advantages of my invention may be obtained in a somewhat imperfect manner by replacing the spiral or helix of the filament by a zig zag arrangement as shown in Fig. 5, or by any other arrangement by which different parts of the effective portion of the filament extend side by side so as to blanket each other.

While I have shown the improved filament mounted in a tube and protected against excessive temperature during ignition by a baffle plate and windows, the said filament may be mounted and protected in other ways which will be obvious to anyone skilled in the art.

Having now described my invention, what I claim is:

1. In an electrical ignition device, filament supporting conductors and a platinum containing filament of minute cross section the central portion of which is so formed that different parts extend side by side so as to blanket each other, and its ends extend therefrom to said supporting conductors to which they are secured, whereby the length of the filament and its resistance are minimized and excessive losses of heat are avoided, and means for protecting said filament against excessive temperatures during ignition, said means comprising a baffle between said central portion of said filament and the source of gas to be ignited and an air inlet adjacent said filament, substantially as set forth.

2. In an electrical ignition device, a conductive filament having its central portion formed as a helix and ends of substantial length extending therefrom, the axis of said helix extending transversely to a straight line drawn from one extremity of the filament to the other, and a baffle between said helix and the source of gas to be ignited.

3. In an electrical ignition device, a conductive filament of minute cross section having its effective portion formed of parts extending side by side so as to blanket each other, and ends extending therefrom for a substantial distance, whereby heat losses in said effective portion are minimized, and means comprising a baffle between said filament and the gas supply and an air inlet adjacent the filament for protecting said filament against excessive temperatures during ignition, substantially as set forth.

4. In an electrical ignition device, a conductive filament having an effective portion formed with one or more convolutions and ends of substantial length extending therefrom in substantially direct lines to their points of support, and a baffle situated between said effective portion and the source of gas to be ignited.

5. In an electrical ignition device, a conductive filament having an effective portion formed with one or more convolutions and

ends of substantial length extending therefrom in substantially direct lines to their points of support, a baffle situated between said effective portion and the source of gas to be ignited, and one or more apertures adjacent said filament for admitting atmospheric air into proximity thereto.

6. In an electrical ignition device, filament supporting conductors, and a conductive filament of minute cross section the central portion of which is so formed that different parts extend side by side so as to blanket each other, and its ends extend therefrom in substantially direct lines to said supporting conductors to which they are secured, the length of said ends being

sufficient to prevent the central portion from being chilled by the proximity of said supporting conductors, and means for protecting said filament against excessive temperatures during ignition, said means comprising a baffle between the central portion of the filament and the source of gas to be ignited and an air inlet adjacent said central portion, substantially as described. 20

Correction in Letters Patent No. 1,118,942.

It is hereby certified that in Letters Patent No. 1,118,942, granted December 1, 1914, upon the application of Howard Lyon, of Gloucester City, New Jersey, for an improvement in "Ignition Devices," an error appears in the printed specification requiring correction as follows: Page 1, line 43, for the word "line" read *fine*; and that the said Letters Patent should be read with this correction therein that the same may conform to the record of the case in the Patent Office.

Signed and sealed this 12th day of January, A. D., 1915.

[SEAL.]

R. F. WHITEHEAD,
Acting Commissioner of Patents.
